PHONOGRAPH PICKUP ARM

Joseph Palma, Jr., Wheaton, Ill., assignor to Shure Brothers Incorporated, Evanston, Ill., a corporation of Illinois

Application August 1, 1956, Serial No. 42,480

Term of patent 14 years

(Cl. D26—14)

Fig. 1 is a side elevational view of a phonograph pickup arm showing my new design:

Fig. 2 is a plan view;

Fig. 3 is an elevational view of the other side thereof;

Fig. 4 is a front elevational view taken in the direction indicated by lines 4—4 in Fig. 1;

Fig. 5 is a cross-sectional view taken on line 5—5 of Fig. 4; and

Fig. 6 is a cross-sectional view taken on line 6—6 of Fig. 2.

I claim:

The ornamental design for a phonograph pickup arm, substantially as shown.
